UNITED STATES PATENT OFFICE.

GRACE TANCILL, OF ST. LOUIS, MISSOURI.

DESIGN FOR A DRESS.

Application filed February 1, 1926. Serial No. 16,362. Term of patent 3½ years.

To all whom it may concern:

Be it known that I, GRACE TANCILL, a citizen of the United States, residing in the city of St. Louis and the State of Missouri, have invented a new, original, and ornamental Design for Dresses, of which the following is a specification, reference being had to the accompanying drawing, forming part thereof.

The figures show a front and a back view of a dress, showing and embodying my new design.

I claim:

The ornamental design for a dress, as shown.

GRACE TANCILL.
